US00D470845S

(12) **United States Design Patent** (10) Patent No.: **US D470,845 S**
Hyun (45) Date of Patent: **** Feb. 25, 2003**

(54) **WIRELESS KEYBOARD FOR PORTABLE TELEPHONE**

(75) Inventor: **Sang Min Hyun**, Seoul (KR)

(73) Assignee: **Samsung Electronics Co., Ltd.**, Suwon (KR)

(**) Term: **14 Years**

(21) Appl. No.: **29/140,356**

(22) Filed: **Apr. 17, 2001**

(51) LOC (7) Cl. **14-02**

(52) U.S. Cl. **D14/393**; D14/240

(58) Field of Search D14/137, 138, D14/218, 147-148, 247-248, 391-394, 144, 320, 396, 341-347, 399, 379/433.01-433.13, 419, 434, 428.01-428.04, 420.01-420.04, 440; 455/550-575, 90; D21/517; 361/680; 341/22; 345/168, 169

(57) **CLAIM**

I claim the ornamental design for a wireless keyboard for portable telephone, as shown and described.

DESCRIPTION

FIG. 1 is a perspective view of a wireless keyboard for portable telephone showing my new design;

FIG. 2 is a front elevational view thereof; (A rear elevational view is symmetrical to the front elevational view)

FIG. 3 is a left-side elevational view thereof;

FIG. 4 is a right-side elevational view thereof;

FIG. 5 is a top plan view thereof; and,

FIG. 6 is a bottom plan view thereof.
